LYMAN CLARK, OF PINE ISLAND, MINNESOTA.

Letters Patent No. 79,206, dated June 23, 1868.

IMPROVED CAR-BRAKE.

The Schedule referred to in these Letters Patent and making part of the same.

TO ALL WHOM IT MAY CONCERN:

Be it known that I, LYMAN CLARK, of Pine Island, in the county of Goodhue, and State of Minnesota, have invented a new and useful Improvement in Car-Brakes; and I do hereby declare that the following is a full, clear, and exact description thereof, which will enable others skilled in the art to make and use the same, reference being had to the accompanying drawings, forming a part of this specification.

The object of this invention is to furnish a brake for stopping cars on railroads, and the invention consists in operating friction-wheels or rolls in contact with the truck-wheels of the car in such a manner that the brakes may be thereby applied at one and the same time to a train of cars or to a single car, as may be desired, and in the manner hereinafter described.

Figure 1 represents a vertical longitudinal section of a train of two railroad-cars with my brake attached, the section being through the line $x x$ of fig. 2.

Figure 2 is a top or plan view of the same.

Similar letters of reference indicate corresponding parts.

A represents the truck-wheels of the railroad-cars.

B, the framework of the truck.

C represents the friction-wheels or rolls which I apply to the truck-wheels, by which the brakes are operated.

D represents the brakes.

The brake-bars D' are attached to the frame of the truck by straps of iron, being near to the peripheries of the wheel when not in actual use. The brakes or friction-shoes D, which are brought in contact with the truck-wheels when in use, are attached to the ends of the brake-bars D'.

F represents the shafts of the friction-rolls C.

G represents ropes or chains which pass through or are attached to the shafts F, the ends of which ropes or chains are attached to the brake-bars D', as seen in the drawing.

The friction-rolls C are attached by their shafts F to frames marked H, in the drawing, on which frames the said shafts have their bearings, and by which they are supported and controlled.

It will be seen that when the friction-rolls C are lowered or brought in contact with the revolving truck-wheels, the shafts F, to which the rolls are attached, will be rotated, which will wind up the rope or chain around the shaft E, as seen in the drawing, and consequently draw the brakes toward and in contact with the car-wheels, thereby creating friction sufficient to stop the cars.

On the brake-bars D' there are placed elliptic springs d', with which the ropes or chains are connected, the tension of which serves to take off the sudden tension or strain on the brake-chains when the brakes are applied while the train is under a high rate of speed.

The frames H are attached to the truck at one end by a joint, as seen at a. At the other end they are connected by a rope or chain, f, with a shaft marked J, which passes through or is supported by the framework of every car, as seen in the drawing.

By revolving this shaft the chain f will be wound around it and the frame H, and roll C raised thereby. For the purpose of braking or stopping all the cars in a train simultaneously, these shafts J are connected together by universal joints K, so that the engineer or other person may apply the brakes when necessary, and the arrangement is such that the brakes may be applied to all the cars in the train from any one of the cars, for each car is provided with a hand-wheel and shaft, with a worm-screw, which engages with a pinion on the shaft J.

This arrangement is seen in fig. 1.

L is the hand-wheel.

M is the vertical shaft.

N is the worm-wheel on the shaft.

l is the pinion.

The universal joint K allows of the lateral and vertical or irregular up-and-down motion inseparable from railroad-cars.

The shaft m is supported from the platform or by the truck-frame, and the arrangement does not differ materially from that in common use as regards position and the manner in which it is supported.

To provide for the irregular longitudinal motion of the cars back and forth, which invariably occurs in trains, I form an extension-joint in the shaft J, which is marked o, which enables the cars to approach towards or recede from each other any distance which is allowed by the car-coupling or coupling-link.

This extension-joint is formed of two rods p p, fig. 1, and a rod, p'.

r is a head-bar, which is rigidly attached to the rod p', and which slides on the rods.

s is another head-bar, to which the rods are attached at one end, and through which the rod p' slides.

The other ends of the rods p p are rigidly attached to the universal joint K, as seen in the drawing.

It will be seen that, should the cars (fig. 1) approach each other, the rod marked p' will slide through the head-piece s, and that the head-piece r will slide on the rods p p, thus allowing of longitudinal motion, and at the same time allowing a rotary motion to the shaft J.

The upright shaft m is rotated by the hand-wheel L, and the worm-wheel is thrown out of gear with the pinion l on the shaft J by a shifter (not seen in the drawing) when the brakes are to be applied.

This is for the purpose of applying the brakes in less time than it can be done by reversing the worm-wheel.

Having thus fully described my invention, I claim therein as new, and desire to secure by Letters Patent—

The friction-wheels or rolls C and shaft F, combined with the wheels of a railroad-car, and with the brakes controlling the same, when operated by a chain or cord winding upon a horizontal rod or shaft beneath the car, substantially in the manner and for the purpose herein set forth.

The above specification of my invention signed by me, this 20th day of June, 1867.

LYMAN CLARK.
